UNITED STATES PATENT OFFICE.

GEORGE S. POWER, OF NUTLEY, NEW JERSEY.

FLUID-MOVED VALVE.

1,104,131.

Specification of Letters Patent. Patented July 21, 1914.

Application filed October 8, 1913. Serial No. 794,010.

To all whom it may concern:

Be it known that I, GEORGE S. POWER, a citizen of the United States, and resident of Nutley, in the county of Essex and State of New Jersey, have invented certain new and useful Improvements in Fluid-Moved Valves, of which the following is a specification.

This invention relates to a fluid moved valve, which is particularly applicable to a reciprocating piston and cylinder. Its organization comprises a valve with a pair of members each of which comprise at least one conical frustum, the surfaces of which are reversed to each other. The said frustums have impinged thereon an actuating fluid, the longitudinal components of the impulses of the actuating fluid, augmenting the reciprocations of said valve. The valve principally receives its reciprocations from the effect of the flow of the fluid through the contracted area between its outer periphery and the top, bottom and side walls of the chamber in which it reciprocates as will be explained.

In the accompanying drawings Figure 1 represents a top plan view of a cylinder and its appurtenances with the invention incorporated therewith, Fig. 2 shows a partial section of Fig. 1 on the line 2, 2, Fig. 3 is a section as on the line 3, 3 of Fig. 2, Fig. 4 represents a partial section of Fig. 2 on the line 4, 4 and Fig. 5 shows an enlarged longitudinal section of a modification of the invention.

A cylinder is indicated at 20 with the longitudinal port 21 having the inlet end 22 and outlet end 23, the longitudinal port 24 having the inlet end 25 and the outlet end 26, the exhaust port 27 with the threaded portion 28 and the exhaust port 29 with the threaded portion 30.

A back cylinder head is shown at 35, and a front cylinder head 36 has formed therewith a stuffing box 37 with the gland 38. A piston 40 in said cylinder has extending therefrom the piston rod 41 which extends through the stuffing box 37 and gland 38 in the usual manner. A main driving fluid supply port 44 has connected thereto the driving fluid supply pipe 45. A valve chest 47 with the central port 48 is belted to the cylinder 20 by means of the bolts 49. The valve chest 47 has in threaded engagement therewith the cylinder heads 50 and 51. The cylinder head 50 has formed therewith

the valve seat 52 and the radial ports 53 for the chamber 54. The cylinder head 51 has formed therewith the valve seat 58 and the radial ports 60 for the chamber 59. A central inlet sleeve 62 with the inlet ports 63 and 64 radially distributed and the tapering ends 65 is located in the valve chest 48 between the inner accompanying ends of the cylinder heads 50 and 51. A guide bolt 67 with the head 68 and nut 69 located and supported in the axial centers of the valve chest 47 and cylinder heads 50 and 51. Upon the guide bolt 67 is slidably supported a valve with oppositely positioned conical frustums. Specifically the valve comprises two members with the reversed positioned conical frustums 70 and 74. Against the larger end of the frustum 70 is located the projecting collar 72 with the conical frustum 71 and collar 73. Against the larger end of the frustum 74 is located the projecting collar 76 with the conical frustum 75 and collar 77. A sleeve 80 separates the two members or frustums 70 and 74 of the valve.

In the modification shown in Fig. 5 the members of the valve comprise detachable units and consist of the supporting barrel 85 with the head 86. The barrel supports the detachable conical frustums 87 and 90. Against the larger end of the frustum 87 is located the projecting collar 89 with the conical frustum 88. Against the larger end of the frustum 90 is located the projecting collar 92 with frustum 91. A sleeve 93 separates the frustums 87 and 90, and a locking collar 94 in threaded engagement with the barrel 85, locks all the elements securely on said barrel. The object of the detachable units of this modification is to be enabled to dispense with some of said units or to vary their dimensions. For instance, the primary essential units of the valve are the projecting collars 72 and 76, in the form of valve shown particularly in Fig. 2 and the projecting collars 89 and 92 shown in Fig. 5. In Fig. 2 all the other elements of the valve except the collars 72, 76 and the sleeve 80 or its equivalent might be dispensed with, and in Fig. 5 all the elements of the valve except the collars 89, 92 and some connecting means might be dispensed with.

To use the invention steam, air or other suitable fluid is supplied by the pipe 45 which enters the supply port 44 and the central port 48 and from thence passes

22 through the radial inlet ports 63 and 64 of the inlet sleeve 62. The piston 40 and the valve on the guide bolt 67 may be considered located as shown in Fig. 2, and jets of fluid indicated at 96 flow through the ports 63 impinging against the conical frustum 70, while jets of fluid 97 flow through the ports 64 impinging against the sleeve 80. The components, parallel to the longitudinal axis 10 of the valve, of the jets of fluid 96 assist in forcing the valve in the direction of the arrow A. The impingement of the fluid on the face of the collar 72 adjacent to the large end of the frustum 70, with the effect 15 of the flow of the fluid over its edges forces the valve in the direct line of action thereof. The fluid when it passes the edge of the collar 72 flows into the chamber 59, and on account of the contracted area between said 20 collar 72 and sleeve 62 moves the valve in the direction of the arrow A. With the valve located as shown in Fig. 2 the jets 97 do not coat with the frustum 74 and therefore no immediate retardation results from 25 the latter jets of fluid, but the valve is quickly and effectively forced to seat itself on the valve seat 58. When the valve has been seated upon the valve seat 58, sufficient fluid has entered the chamber 59 and 30 from thence has flowed through the ports 60 and 21 to drive the piston 40 to the other end of its stroke in the direction of the arrow B. When the piston has reached its position adjacent to the cylinder head 35, 35 the exhaust port 27 is open, which discharges the fluid between the piston 40 and the cylinder head 37 and reduces the pressure of the fluid in the chamber 59. The valve now having been moved so as to seat 40 itself on the valve seat 58, the fluid from the central port 48, flowing through the ports 63 and 64 enters the chamber 54 and from thence through the ports 58 in to the port 24, and from the latter enters the cylinder to drive the piston to the position 45 shown in Fig. 2. The valve when in the position opposite to that shown in Fig. 2 and after having performed its function to drive the piston in the direction of the arrow B, is acted upon by the jets 97 to move said valve in the direction of the arrow C and seat it upon the valve face 52. During the latter movement of the valve the jets 96 assist to drive the valve in the direction of the arrow C, and the piston 40 is 55 moved in the direction of the arrow B.

The modification may be further modified by eliminating the frustums 87, 88, 90 and 91 and retaining only the projecting 60 collars 89 and 92 so that the valve would be reciprocated toward a port which is uncovered in the valve chest by the action of the fluid drawing the valve toward the uncovered port by reason of the friction or 65 suction produced in the annular contracted

area between the outer surface of the collar adjacent to the uncovered port and the wall of the valve chest or the sleeve therein.

Having described my invention what I desire to secure by Letters Patent and 70 claim is:

1. In an apparatus of the character described the combination of a cylinder having inlet and exhaust ports, a valve chest for said cylinder, a valve in said chest, oppositely positioned faces for said valve and means to alternately impinge jets of fluid against the faces of said valve to give the initial impetus to said valve for each of its reciprocations. 80

2. In an apparatus of the character described the combination of a cylinder having inlet and exhaust ports, a valve chest for said cylinder, a valve in said valve chest having reversed tapering faces, a sleeve in 85 said chest with ports to enable a fluid to alternately impinge against said tapering faces.

3. In an apparatus of the character described the combination of a cylinder having inlet and exhaust ports, a valve chest for said cylinder, a fluid moved valve in said valve chest, reversed tapering faces for the valve and a sleeve in said chest having two sets of ports, the fluid from one set 90 of ports striking one of the tapering faces and the jets from the other set of ports simultaneously avoiding the other tapered face of the valve, the valve reciprocating with the alternate effects of the jets. 100

4. In an apparatus of the character described the combination of a cylinder, ports for the cylinder, a valve chest for the cylinder, a sleeve in the valve chest having two ports, a slidably movable valve in the valve 105 chest and a pair of reversed frustums for the valve alternately in the paths of jets of fluid discharged from the ports in said sleeve.

5. In an apparatus of the character described the combination of a cylinder, ports for the cylinder, a valve chest for the cylinder having two inlet ports coacting therewith, a reciprocating valve in the valve chest, a guide for the valve and a pair of reversed 110 tapering faces for the valves that are alternately actuated by fluid from one of the said inlet ports. 115

6. In an apparatus of the character described the combination of a cylinder, inlet and exhaust ports for the cylinder, a valve chest for the cylinder, chambers in the valve chest coacting with the inlet ports of the cylinder, a guide in the valve chest, a reciprocating valve coacting with said guide, the said valve comprising a pair of accompanying reversed frustums, a projecting collar at the large end of each frustum, a second frustum with its large end adjacent to the 120 collar, a sleeve having two sets of ports to 125 130

- alternately impinge jets of fluid against one of the pair of frustums, and valve seats for ports leading into said chamber coacting with the said second frustums.
- 6 7. In an apparatus of the character described the combination of a cylinder, ports for the cylinder, a valve chest for the cylinder, two inlet ports for a fluid for the valve chest, a guide in the valve chest, and
- 10 a valve coacting with said guide, comprising a pair of detachable reversed tapering faces.
8. In an apparatus of the character described the combination of a cylinder, ports for the cylinder, a valve chest for the cylinder, two sets of inlet ports for a fluid for the valve chest, a guide in the valve chest and a valve coacting with said guide comprising a pair of detachable reversed conical frustums, a separator between said frustums, a detachable projecting collar at the larger end of each frustum and a second frustum with its larger end against the opposite face of each projecting collar and 25 means to lock the detachable elements of the valve together.
9. In an apparatus of the character described the combination of a cylinder, ports for the cylinder, a valve chest for the cylinder, a sleeve with two sets of ports in the valve chest, a guide bolt in the valve chest, a reciprocating valve on the guide bolt comprising a barrel having a head at one end and a threaded portion at the other, a sleeve 30 on the barrel, reversed tapered conical frustums on the barrel on the opposite ends of the sleeve, a projecting collar bearing against the large end of each frustum, a second tapered conical frustum bearing on 35 the opposite side of each collar and a second frustum bearing against said collar reversed to the other frustum bearing against said collar, and a threaded collar registering with the threaded portion of the 40 barrel to lock the ports of the valve together.
- 45 10. In an apparatus of the character described the combination of a cylinder, a valve chest for the cylinder, a valve in said chest proportioned to obtain a contracted area between the outer surface of the valve 50 and the inner surface of the valve chest, said valve having reversed tapering faces and means to alternately direct jets of fluid against said faces.
11. In an apparatus of the character described the combination of a cylinder, a valve chest for the cylinder, a sleeve within the cylinder having two ports, a valve in the sleeve proportioned so as to form a contracted area between the inner surface of 55 the sleeve and the outer surfaces of the valve, a pair of reversed tapering faces for the valve in the path of said ports so that fluid flowing from said ports alternately actuate the said reversed faces of the valve 60 to reciprocate the latter in conjunction with the acceleration imparted to the valve by virtue of the fluid flowing through the contracted areas when escaping from the valve 65 chest.
- 70 12. In an apparatus of the character described the combination of a cylinder, a valve chest for the cylinder, a pair of inlet ports and a pair of outlet ports for the valve chest coacting with the cylinder, a reciprocating valve in the valve chest proportioned 75 so as to form at its opposite ends contracted areas with the inner wall of the valve chest, the said valve actuated by a fluid flowing through the inlet ports and thence through 80 the said contracted areas on its way to said outlet ports.
- Signed at the borough of Manhattan in the county of New York and State of New York this 30th day of September, A. D. 85 1913.
